Primary Examiner — Jae Liang*Assistant Examiner* — Christopher Torma(74) Attorney, Agent, or Firm — Jose Cherson Weissbrot(57) CLAIM

The ornamental design for a sectional sofa as shown and described.

DESCRIPTION

FIG. 1 is a top perspective view of a sectional sofa showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of the circled portion in FIG. 1; FIG. 9 is an enlarged view of the circled portion in FIG. 2; and,

FIG. 10 is an enlarged view of the circled portion in FIG. 7. The small, evenly spaced dashed broken lines in the drawings illustrate portions of the sectional sofa that form no part of the claimed design.

The large, evenly spaced broken lines encircling portions of the sectional sofa in FIGS. 1, 2, and 7 and illustrated in enlarged views in FIGS. 8, 9, and 10 form no part of the claimed design.
